US00D509790S

(12) United States Design Patent **(10) Patent No.:** **US D509,790 S**
Sakai **(45) Date of Patent:** **** Sep. 20, 2005**

**(54) BATTERY CHARGER FOR ELECTRONIC
CAMERA**

(75) Inventor: **Masayuki Sakai, Tokyo (JP)**

(73) Assignee: **Fuji Photo Film Co., Ltd., Kanagawa
(JP)**

(**) Term: **14 Years**

(21) Appl. No.: **29/218,358**

(22) Filed: **Dec. 2, 2004**

(30) Foreign Application Priority Data

Jun. 4, 2004 (JP) 2004-016672

(51) LOC (8) Cl. **13-02**

(52) U.S. Cl. **D13/108**

(58) Field of Search D13/107-110,
D13/118-119, 184; D14/251, 253; D16/219,
237, 242; 320/107-115
